UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

MULTIPLE STEREOTYPE PLATE CASTING AND FINISHING MACHINE

Application filed September 10, 1926. Serial No. 134,696.

This invention relates to that type of stereotyping plants represented in my prior application Serial No. 121,403, filed July 9, 1926, in which a plurality of casting boxes are used with a single finishing machine and relative movement is obtained to provide for delivering first from one casting box and then another to the finishing machine. This invention involves the carrying out of that idea in other forms and particularly to provide constructions taking up comparatively little room thus fitting them for particular places in which they are to be installed. I have shown several forms of the invention for these purposes.

Other objects and advantages of the invention will appear hereinafter.

Reference is to be had to the accompanying drawings in which

20 Fig. 1 is a plan of a preferred embodiment of this invention in which the motion is all rectilinear and the casting machines are located with their axes parallel to each other;

25 Fig. 2 is a plan of a modification of the same in which the same results are secured but in another way;

30 Fig. 3 is a plan of a plant coming within the scope of this invention in which the casting boxes are swung about the finishing machine for the same purpose;

Fig. 4 is a plan of a modification of the form shown in Fig. 3 in which the casting boxes are swung about the melting pot as a center; and

35 Fig. 5 is a plan of a construction in which the finishing machine is swung about the melting pot as a center.

In all these devices there is a relative movement between the casting and finishing machines for the purpose of getting them into registration at the time of delivery and permitting of the pumping of metal into one of the casting boxes at the proper time to allow the casting to cool before the delivery. The finishing machine also moves as it finishes the casting preferably.

Referring to Fig. 1 I have shown two casting boxes 10, although any number can be used, arranged with their axes parallel. They are connected with the melting pot 11 which

has a number of pumps 12 corresponding with the number of casting boxes. Thus they can deliver metal to the casting boxes at any desired time. Adjacent to the delivery ends of the casting machines and arranged transversely across are a pair of rails 13 having racks 14 along them. They are shown in this instance as having racks on their outer edges. A single finishing machine 15 is provided with rolls so that it can be supported by and run along this track from one casting box to the other and will come into line with them alternately. For operating them, a motor (not shown) is provided on the finishing machine movable with it and operating a vertical shaft 16. The shaft is provided with a sprocket wheel and connected by a chain 17 with another sprocket wheel 18 at the other side. These sprocket wheels, or the shafts on which they are mounted, are provided with pinions 19 meshing with the two racks 14. Consequently when the shaft 16 is turned the whole finishing machine will be translated along the tracks 13 from one casting box to the other. I have not shown herein any automatic or other means for controlling the operation, as devices can be used similar to those shown in my prior applications for that purpose. It will be seen that the finishing machine can be moved into registration with each of the casting boxes to receive a plate therefrom and then it can be moved over to the other. The finishing operation is performed or partly performed during that motion. The casting is then delivered from the finishing machine and a new casting introduced into it from the other casting machine.

In the form shown in Fig. 2, practically the same conditions exist. The same pump 12, casting box 10 and finishing machine 15 are shown, but here the two casting boxes are mounted to roll on two transverse rails 23. In this case the two casting boxes are connected together by a frame so that they will move along the tracks and between the pump and the finishing machine. On the frame are two racks 24. In this case only one operating means is required. This comprises the stationary vertical shaft 16 oper-

ated by the finishing machine. This shaft through bevel gears 27 drives a shaft 28. This shaft is provided with two pinions 29 engaging the racks and is held in stationary bearings.

The rotation of this shaft in either direction from the shaft 16 will move the racks back and forth and therefore move the two casting boxes laterally on the tracks from one position to the other. They are shown in a position in which one casting box is in position to receive molten metal and deliver its plate to the finishing machine. When that is done, the two boxes will be moved over to the dotted line position and the other box will be ready to receive a charge of metal from the pump, cool it, and deliver it to the finishing machine.

In the form illustrated in Fig. 3 also a stationary finishing machine 15 is shown and a stationary pump 12 with casting boxes 10 movable between the two. In this case the same mechanism is employed except that the track 33 and the movable rack 34 are curved so that the boxes are moved about a center which in this case is located at the other end of the finishing machine. The operation otherwise is actually the same as in Fig. 2.

In Fig. 4 the same casting boxes 10, pump 12 and finishing machine 15 are shown, but in this case three casting boxes are shown instead of two. Furthermore, the track 43 and the rack 44 curve about the center of the melting pot. The operation can be an intermittent one about the entire circle if desired, or an oscillating motion about the center. The parts are operated by the shaft 16 but the connections shown in the other figures are not illustrated in detail in this figure.

In the form shown in Fig. 5, a single melting pot 21 is shown having three pumps 12 delivering to three casting boxes 10 fixed in radial position around the furnace or melting pot. Around the ends of the casting boxes are two tracks 53 and racks 63 centered about the melting pot and on these tracks is mounted the finishing machine 15 which is provided with an operating mechanism similar to that shown in the other figures. They are operated in this case by the shaft 16 which by bevel gears 57 operates a cross shaft 58 and pinions 59 meshing with the two racks. These pinions are of slightly different diameter on account of the different length of travel of the racks. In all these cases the general principle is the same. A single finishing machine has delivered to it the plates from a plurality of casting boxes. The finishing machine and casting boxes are intermittently brought into alignment for the delivery of the plate from one to the other. The finishing machine is always adapted to start up immediately and finish the plate while the traverse, or part of it, is being ac-

complished. Thus another casting box with a plate therein is brought into position to deliver to the finishing machine.

Although I have illustrated and described several embodiments of this invention, I am aware of the fact that other modifications can be made therein by any person skilled in the art without departing from the scope of the invention as expressed in the claims. Therefore I do not wish to be limited to all the details of construction herein shown and described, but what I do claim is:—

1. In a plant for making stereotype printing plates, the combination of a pair of casting boxes and a finishing machine, of a pair of racks, a pair of pinions meshing with said racks, means for rotating said pinions to secure a relative side-ways translating movement between the pinions and racks, the racks being connected with the plate making apparatus to transfer a part of it with them.

2. In a stereotype plate making apparatus, the combination with two stationary casting machines arranged with their axes parallel, a pair of transverse tracks, and a finishing machine movable along said tracks from a position in alignment with one casting machine to a position in alignment with the other.

3. In a stereotype plate making apparatus, the combination with two stationary casting machines arranged with their axes parallel, a pair of transverse tracks having racks thereon, a finishing machine movable along said tracks from a position in alignment with one casting machine to a position in alignment with the other, a shaft connected with the finishing machine and adapted to be rotated when the finishing apparatus is in operation, and pinions meshing with the two racks and operated by said shaft for moving the finishing machine along the tracks.

4. In a stereotype plate making plant, the combination of a melting furnace, a plurality of pumps therein, a series of casting boxes radially arranged with respect to the melting furnace, and spaced therearound in stationary position, two curved tracks concentric with the melting furnace and located beyond the ends of the casting boxes, and a finishing machine mounted to roll in the arc of a circle around said tracks, from radial alignment with one casting box to alignment with another.

5. In a stereotype plate making plant, the combination of a melting furnace, a plurality of pumps therein, a series of casting boxes radially arranged with respect to the melting furnace and spaced therearound in stationary position, two curved tracks concentric with the melting furnace and located beyond the ends of the casting boxes, a finishing machine mounted to roll in the arc of a circle around said tracks, and having a shaft pro-

vided with two pinions, the tracks being provided with racks in which the pinions engage to roll therealong and translate the finishing machine therewith, and means on the finishing machine for rotating the shaft when the finishing machine is operating, whereby the finishing machine will move from radial alignment with one casting box to alignment with another.

10 In testimony whereof I have hereunto affixed my signature.

HENRY A. WISE WOOD.
